UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR LOCK.

Application filed March 18, 1922. Serial No. 544,846.

To all whom it may concern:

Be it known that I, NORMAN B. HURD, a citizen of the United States of America, residing at New Britain, Conn., have invented a new and useful Door Lock, of which the following is a specification.

My invention relates to improvements in locks which are particularly useful for automobile doors. My object is to provide a construction which is simple, inexpensive, and capable of easy and sure operation, the invention relating more particularly to the latch and latch dog construction, as will be more fully explained hereinafter.

15 In the drawings:

Fig. 1 is a side elevation of my improved lock with part of the housing removed to show the internal parts.

20 Fig. 2 is a section on the line 2—2 of Fig. 1, showing certain parts in elevation.

Fig. 3 is an end elevation of certain parts.

Fig. 4 is a perspective view of the latch bolt and dogging device.

1 is the latch case, which constitutes a 25 housing and support for the various internal parts. 2 is a longitudinally movable spring latch bolt, which projects through the face plate 3 of the lock. 4 is a spring for normally impelling the latch bolt 2 forwardly.

30 5 is a latch retracting lever. 6 represents a roll-back arm, which is operated by a suitable knob or handle at the inside of the door, and 7 represents a roll-back arm operated by a suitable outside knob or handle. 35 These roll-back arms make suitable engagement with the latch retracting lever 5 to move it in the latch retracting direction, while the spring 8 moves said lever in the opposite direction. The lower end of the 40 latch retracting lever 5 is arranged to engage a shoulder 9 on the tail of the latch bolt to retract the latch.

45 Pivottally mounted directly on the latch bolt is a dog, which functions to hold the latch in its projected position, so that it cannot accidentally work back and release the door when the same is closed. This dog is both manually and automatically operated, that is to say, when the door is being 50 closed it is automatically thrown off as soon as the strike plate is encountered, so that a further door closing movement may force the latch back without danger of injury. The dog is also manually retracted

whenever the latch retracting lever 5 is moved in a retracting direction, so as to first release the dog to permit the latch to be thereafter retracted by hand. At all other times the dog serves to effectively hold the latch in its projected position.

60 While, broadly speaking, dogging devices for this purpose are not new, the novelty herein resides in the new construction and arrangement of parts disclosed. In the particular form shown herein, the dog comprises a bell crank lever pivoted at 10 to swing horizontally on the upper side of the latch bolt and move with said bolt. The rear end of the dog is provided with a locking nose 11, which is arranged to take into a 70 recess in the side wall of the lock case, two of such recesses being indicated at 12—12. Depending from the opposite end of the dog is a shoulder 14, and located between this shoulder and the body of the latch bolt 75 is a small spring 15, which functions to yieldingly move the dog normally in the dogging direction. 16 is what I may term a latch actuator, or anti-friction device, which comprises a segment shaped piece pivoted to the lock case at 17, having therein a 80 radial cam slot 18. This actuator 16 is preferably located in a horizontal slot in the latch bolt head 2. 19 is a pin carried by the latch bolt head and passing through the 85 slot 18 in the actuator, as best seen in Fig. 2. This actuator 16 also bears against the forward side of the shouldered portion 14 on the latch dog.

85 In operation, assuming the parts stand as shown in Fig. 2 and the door to which the latch is applied is open, it is obvious that the latch bolt head 2 cannot be pushed back by any pressure applied to the outer end. If the door is closed, the actuator 16 will 90 first hit the strike plate S so that as the door continues to close, the actuator 16 will be rocked back. The first part of this rocking movement will tilt the latch dog so as to release it from the latch case. Continued 95 movement of the door in the closing direction will cause the actuator 16 to continue to swing back, the effect of which will be to repress the latch 2 through the medium of the pin and cam slot connection previously 100 described. The rear end of the actuator is rounded so that it will not crowd against the shoulder 14 to the injury thereof as it re-

cedes. As soon as the door is fully closed, obviously the latch bolt 2 will be projected ahead into the keeper slot of the strike plate in the usual manner. This will permit the 5 actuator 16 to resume the position shown in that figure. So long as the door is closed, it is obvious that the latch bolt head 2 cannot be accidentally or unintentionally repressed to the point where the door might 10 be released.

When it is desired to open the door the latch retracting lever 5 is actuated by either of the roll backs 6 or 7. The first rearward movement of the lower end of the lever 5 15 will cause said end to engage an incline or bevel 21 just forward of the locking nose 11, so that said nose will be cammed back out of the locking position, before said lever 5 actually encounters the shoulder 9. When 20 said dog has been freed from the side of the housing, the retracting lever 5 will encounter the shoulder 9, and a continued swinging movement of said retracting lever will withdraw the latch 2.

25 It should be observed that in the form shown the slot 18 is of sufficient width to permit of a sufficient independent movement of the actuator 16 relatively to the latch so that the first movement of the actuator will 30 be to free the dog and thereby release the latch for repression by the actuator. The arrangement is such that friction is very greatly reduced, therefore, the actuator may 35 properly be termed an anti-friction device even though friction is not wholly eliminated. By the provision of such a device a more powerful spring 4 can be successfully employed than would otherwise be practical and of course this is advantageous in such 40 uses as demand liability of action, as for example, use on an automobile door.

Obviously, I have shown my invention in only one form, and wish to have it understood that in many respects the form and 45 arrangement may be modified without departing from the spirit or scope of the invention as disclosed and claimed.

What I claim is:

1. In a lock, a case, a sliding spring latch bolt carried thereby, a pivotally mounted anti-friction latch retracting actuator, means of connection between said actuator and latch bolt to transform the rotary movement of said actuator into rectilinear movement of said bolt, a dog pivotally mounted 50 upon and carried by said latch bolt, an abutment against which said dog normally engages to hold said latch bolt projected, and operative means of connection between said actuator and said dog to release the latter 55 preparatory to the repression of said bolt by said actuator.

2. In a lock, a case, a sliding spring latch bolt carried thereby, a pivotally mounted anti-friction latch retracting actuator, means 60 of connection between said actuator and latch bolt to transform the rotary movement of said actuator into rectilinear movement of said bolt, a dog pivotally mounted upon 65 and carried by said latch bolt, an abutment against which said dog normally engages to hold said latch bolt projected, operative means of connection between said actuator and said dog to release the latter 70 preparatory to the repression of said bolt by said actuator, and a manually operable means arranged to retract said latch, said means 75 cooperating with the said dog to release the same preparatory to retracting the bolt.

3. In a lock, a casing, a spring projected 80 reciprocating latch bolt carried thereby, a swinging anti-friction latch actuator also carried thereby and cooperating with said latch to repress the same when said actuator is swung in one direction, a horizontally 85 swinging dog pivotally mounted on the latch bolt and movable therewith, an abutment arranged to be normally engaged by said dog when the latch bolt is fully projected, an operative means of connection between 90 the actuator and the dog to release the same preparatory to the repression of the latch bolt.

NORMAN B. HURD.
